UNITED STATES PATENT OFFICE.

BOSIAR LEE FIKES, OF ROYSE CITY, TEXAS.

COTTON-CHOPPER.

SPECIFICATION forming part of Letters Patent No. 790,355, dated May 23, 1905.

Application filed April 5, 1904. Serial No. 201,770.

To all whom it may concern:

Be it known that I, BOSIAR LEE FIKES, a citizen of the United States, residing at Royse City, in the county of Rockwall and State of Texas, have invented a new and useful Cotton-Chopping Machine, of which the following is a specification.

This invention relates to cotton-choppers; and it has for its object to present a device of this class which shall possess superior advantages in point of simplicity, durability, and general efficiency.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of embodiment of the invention, it being, however, understood that no limitation is necessarily made to the precise structural details therein exhibited, but that various changes and modifications may be made, especially with regard to size, shape, proportion, and exact manner of assemblage of the parts, when such changes may be resorted to within the scope of the invention and without departing from the spirit or sacrificing the efficiency of the same.

In said drawings, Figure 1 is a vertical longitudinal sectional view of a cotton-chopper constructed in accordance with the principles of the invention. Fig. 2 is a transverse sectional detail view taken on the line 2 2 in Fig. 1. Fig. 3 is a transverse sectional detail view taken on the line 3 3 in Fig. 1.

Corresponding parts in the several figures are indicated throughout by similar characters of reference.

The improved implement which is the subject of the present invention is provided with an approximately rectangular frame, including side members 1 1 and end members 2 3. Suitably connected with the side members 1 1 are spaced downwardly-extending cylinders 4 4 and 5 5, through which extend supporting-rod 6 6 and 7 7. The lower ends of the

supporting-rod 6 6 are connected with an 50 arched front axle 8, carrying wheels 9. A rear axle 10 is supported for rotation at the lower ends of the vertically-movable rods 7. Within the cylinders 4 and 5 are springs 11, which operate to force the respective axle- 55 supporting rods in a downward direction. The rear axle 10 carries a ground-engaging operating-wheel 12.

Slidably engaging the rear axle 10 is a sleeve 13, having a forward projection 14, constituting a socket for the accommodation of a ball 15 at the rear end of a shaft 16, the front end of which is likewise provided with a ball 17, socketed in a recess 18 in the arched front axle. The shaft 15 has a non-circular portion 60 19, upon which is slidably mounted a pinion 20, capable of being secured at any desired adjustment by a set-screw 21, so as to engage any one of a plurality of annular series of cogs 22 upon the adjacent face of the earth-engaging wheel 12. The slide sleeve 13 is adjustable by means of a suitably-disposed lever 23, whereby the rear end of the shaft may be moved laterally, so as to cause the pinion 21 to be moved into or out of engagement with the cogs upon the wheel 12. It is to be understood that the balls at the ends of the shaft 16 are to have sufficient play in their respective sockets to enable the desired adjustment to be made. 70 75 80

The rear end of the frame carries plows or cultivating implements 24, the shanks of which, 25, are suitably connected with said frame.

The shaft 16 carries a plurality of chopping hoes or blades 26, which by preference are spirally disposed and are suitably secured to lugs 27, extending radially from said shaft. 85

The main transporting-wheels of the machine, as shown at 28, are mounted for rotation upon the spindles of an arched axle 29, which is connected, by means of frame-bars, as 30, uprights, as 31, and brace-rods, as 32, with the hereinbefore-described frame, the side members of which are connected by an 90 intermediate cross-bar 33. Pivotedly connected with an upright 31 is a hand-lever 34, connected by rods or links 35 with the upper 95

ends of the axle-supporting rods 6 and 7, which latter may thereby be adjusted vertically and retained at any desired adjustment by means of a spring-actuated dog or pawl 5 36, suitably connected with the lever 34 and engaging a segment-rack 37.

Suitably connected with the frame of the machine is a draft member 38, having a depending bracket 39, provided with a plurality of perforations 40, adapted to be connected, as by means of links 41, with the front axle 8 of the lower frame, to which draft may thus be directly applied.

From the foregoing description, taken in connection with the drawings hereto annexed, the operation and advantages of this invention will be readily understood by those skilled in the art to which it appertains. When the machine progresses over the ground, the arched axle 8 straddles the row of plants to be operated upon and the wheel 12 engages the ground at one side of the row, the front and rear axles having been previously adjusted to and secured at any desired elevation by the means herein described. The ground-engaging wheel 12 causes the chopper-carrying shaft 16 to rotate at any desired speed, which will be regulated by the position of the pinion 21 with relation to the cogs upon the adjacent 30 face of the ground-engaging wheel 12. As the shaft is being rotated the plants will be chopped or thinned in the usual manner, which is well understood. To throw the machine out of gear, the lever 23 may be manipulated 35 to move the rear end of the shaft 16 to one side until the pinion 21 is disengaged from the cogs 22. When the machine is to be transported, the axles 8 and 10 and their related parts may be raised to an out-of-the-way 40 position by manipulating the hand-lever 34, as will be readily understood.

Having thus described my invention, I claim

and desire to secure by Letters Patent of the United States—

1. In a machine of the class described, a 45 frame having two pairs of downward-extending guide-cylinders, spring-actuated supporting-rods supported for vertical movement in said cylinders, an arched wheel-carrying front axle connected with the front supporting-rods, 50 an axle supported for rotation by the rear supporting-rods, a ground-engaging wheel upon said axle having a plurality of annular series of cogs on one side, a sleeve supported slidingly upon said axle, a chopper-carrying shaft 55 provided at its ends with balls socketed in said sleeve and in the arched front axle, and a pinion adjustable upon said shaft.

2. In a machine of the class described, a frame having guide-cylinders, axle-carrying 60 rods supported for vertical movement in said cylinders, a front axle having transporting-wheels, a rear axle having a single ground-engaging operating-wheel provided with series of cogs, a sleeve slideable upon the rear 65 axle, a chopper-carrying shaft provided at the ends thereof with balls socketed in said sleeve and in the front axle, a pinion adjustable upon said shaft and adapted for engagement with the cogs upon the ground-engaging wheel, an 70 arched main axle having main transporting-wheels, means connecting said axle with the frame, a hand-lever, connecting means between said hand-lever and the adjustable axle-carrying rods, and means for securing said 75 hand-lever at various adjustments.

In testimony whereof I have hereunto signed my name to this specification this the 19th day of March, 1904.

BOSIAR LEE FIRES.
